UNITED STATES PATENT OFFICE.

FRANK P. FISH, OF NEW YORK, N. Y.

FIRE-ESCAPE.

SPECIFICATION forming part of Letters Patent No. 256,990, dated April 25, 1882.

Application filed February 21, 1882. (No model.)

To all whom it may concern:

Be it known that I, FRANK P. FISH, of New York city, in the county of New York and State of New York, have invented certain new and useful Improvements in Fire-Escapes, of which the following is a full, clear, and exact description.

My invention relates to that class of fire-escapes which are adapted to be permanently fixed to the outside of the wall of the building; and it has for its object to provide a fire-escape of this character having such construction that it is adapted to unfold and furnish a ladder for easy and safe descent from the windows of the building, and to be drawn together or folded up, when not in use, in such position that it will be practically invisible on the wall of the building.

Reference is to be had to the accompanying drawings, forming part of this specification, in which similar letters of reference indicate corresponding parts in all the figures.

Figure 1 is a front elevation of my new and improved fire-escape, the parts being in position for use. Fig. 2 is a sectional plan view, taken on the line *x x* of Fig. 1, showing the escape attached to the wall of the building. Fig. 3 is a like view, showing the parts in folded position. Fig. 4 is a detailed sectional elevation taken on the line *y y* of Fig. 3; and Fig. 5 is a sectional elevation of the interior side of the wall of the building, showing the means for closing and holding the parts of the escape in folded or closed position and for preventing the movable upright from falling too rapidly, the means for unlocking the movable upright to permit it to drop to position for use, and the means for giving the alarm.

A A' represent the uprights or side bars of the fire-escape ladder, which are semi-cylindrical in cross-section, as shown in Figs. 2 and 3; and B B represent the cross-pieces or rounds, which are hinged at their ends between the edges of the uprights, as shown at *d d*. The uprights are of a length about equal to the height of the building to which the escape is to be attached, and they are built up of sections spliced together by the splice-plates *ff*, which are bolted or riveted to the ends of the sections, as shown in Figs. 1 and 4.

The upright A is adapted to be made fast

to the wall C of the building by the staple-irons *c*, driven into the wall, as shown in Figs. 1, 2, and 3. The upright A' is not attached to the wall, but is left free to swing upon the hinged rounds, so that it may swing out away from the upright A to bring the rounds into horizontal position for use, or be drawn up by suitable means, so that its edges will come against the edges of the upright A, as shown in Figs. 3 and 4, in which position the uprights entirely inclose the rounds, and the escape will present the appearance upon the wall of the building of pipe, similar to a water-pipe, leading from the roof of the building.

The outward movement of the movable upright away from the fixed upright is limited by the irons D D, which are driven into the wall of the building and inclose the two uprights, as clearly shown in Figs. 2 and 3. In most instances, however, the movable upright will be made in such manner that when it swings away from the fixed upright its lower end will rest upon the ground or pavement; but for additional security as many of the irons D as may be considered necessary, according to the height of the building, will be used, and these irons also prevent the movable upright from swinging away from the wall.

The means I employ for folding the escape consists of the small wire cable E, which is attached at its outer end to the movable upright A', about midway of its length, as shown at *e* in Figs. 1 and 4. From this point the cable passes under the pulley f', secured in the upright A; thence up along the inside of the said upright to a point near its upper end, where it passes over the pulley g, also secured in the fixed upright; thence through the perforation h in the upright and the perforation h' in the wall; thence over the pulley g', secured upon the inside of the wall; thence down along the interior of the wall to the lower floor or basement of the building, where it is given a turn around the crank-shaft H, (shown in Fig. 5,) and is provided at its inner end with the counterbalance-weight I, which weight prevents the movable upright A' from falling away from the fixed upright too rapidly, as will be hereinafter described.

The means for holding the escape in folded position consists of the pivoted stop or button

L, which is adapted to be moved under or so as to engage with the crank *i* of the crank-shaft H for holding the shaft from being turned by the weight of the movable upright A', resting upon the cable E, as clearly indicated in Fig. 5.

N represents the cable or wire, by means of which the button or stop L is disengaged from the crank *i* of the crank-shaft H for releasing the cable E for permitting the movable upright A' to drop to position for putting the escape in position for use. This cable or wire N is attached to the button or stop L, as shown in Fig. 5, and passes from that point over the pulleys P P', which are secured to the wall, and thence up along the interior of the wall to the upper story of the building, where it is secured to a pin or similar fastening, as shown at *j* in Fig. 5. This wire or cable is adapted to be pulled from each story of the building for releasing the movable upright for setting the escape in case of fire by means of the small hand cranks or levers J, which are set upon or in the wall, or upon suitable ornamental plates set in the wall, and attached to the wire or cable N, as shown in Fig. 5. When the cable or wire N is given a pull by operating any one of the levers J sufficient to swing the button or stop L upon its pivot sufficient distance to release the crank *i*, the weight of the movable upright A' will cause it to drop or swing away from the fixed upright A. The sudden and heavy fall or drop which the upright A' otherwise would have is checked, so as to prevent any injurious jarring or racking of the escape by the counterbalance-weight I, attached to the inner end of the cable E below the crank-shaft H, as above mentioned, and as shown in Fig. 5. The upward movement of the cable E, caused by the falling of the movable upright

A', is caused to give an alarm in each story of the building by means of the bells K K, which are caused to be struck by the projections *k k*, secured to the cable E in proper position for striking the hammer-crank of the bell, as shown in Fig. 5. By this means all persons in the building may be warned of the fire and their attention called directly to the fire-escape when the escape is set for use.

In order to fold the escape after it has been set for use, or in the first instance, it is only necessary to apply power to the crank *i* of the shaft H, which will draw upon the cable E and raise the movable upright. When the movable upright is drawn to position the button L is to be turned on its pivot under the crank to await the next emergency.

Having thus fully described my invention, what I claim as new, and desire to secure by Letters Patent, is—

1. The combination of an end-notched button, L, and a shaft, H, having a crank arm, *i*, adapted to lock in the notch of said button and to hold the movable upright A' in folded position, as described.

2. The combination, with a wall, C, having pulleys P P' and pin *j*, of the cable N and button L, whereby the upright A' may be unlocked from any story of the building and allowed to drop into position for immediate use, as described.

3. The combination, with a dropping upright, A', of a weighted cable, E, having the projections *k k* and one or more bells, K, whereby the dropping of the upright causes a fire-alarm to be sounded, as described.

FRANK PARRY FISH.
